UNITED STATES PATENT OFFICE.

WILLIAM BEALL GRAY, OF LOUISVILLE, KENTUCKY, ASSIGNOR TO MARTIN J. BANNON, OF LOUISVILLE, KENTUCKY.

REINFORCEMENT FOR PIPE INSULATION.

1,153,159.

Specification of Letters Patent.

Patented Sept. 7, 1915.

Application filed January 29, 1915. Serial No. 5,094.

To all whom it may concern:

Be it known that I, WILLIAM BEALL GRAY, a citizen of the United States, and a resident of Louisville, in the county of Jefferson and State of Kentucky, have invented a new and useful Improvement in Reinforcements for Pipe Insulation, of which the following is a specification.

My invention is an improvement in reinforcements for pipe insulation, and has for its object to provide a device of the character specified, intended for use with pipes having insulating coverings, too soft to hold its form under the weight of the pipe which it covers and adapted to be connected with the pipe and to be arranged between the pipe and a support of the character shown and described in my co-pending application, Serial No. 851,222, filed July 15, 1914.

20 In the drawings: Figure 1 is a perspective view of one embodiment of the invention, Fig. 2 is a similar view of another embodiment, Fig. 3 is a transverse vertical section of a pipe provided with the improvement, and Figs. 4, 5, 6, 7 and 8 are perspective views of other embodiments of the invention.

The embodiment of the invention shown in Fig. 1 comprises a sheet 1 of metal of suitable weight and size, the said sheet being curved transversely as shown, to fit the peripheral surface of the insulation of the pipe. The sheet is provided at each side edge and near its ends with slots 2 for a purpose to be presently described, and ribs 3 are provided on the upper concave surface of the sheet, the said ribs being spaced apart and parallel as shown. The ribs are frusto-pyramidal in cross section arranged with their bases at the sheet and preferably the ribs are as shown in Fig. 1 of considerable length, being almost as long as the sheet. The pipe 4 with which the improvement is designed to be used is provided with the covering 6 of insulating material, as for instance, asbestos, and the ribs 3 are of such height that they will extend through the coverings 6 into contact with the periphery of the pipe. The ribs may be solid or chamfered or recessed longitudinally as shown in Fig. 3, this form being preferable. The slots 2 are designed to receive the ends of tie bands 5 which are passed around the pipe and the insulation for holding the reinforcements in place. The ends of the tie bands

are passed through the slots and are connected in any suitable manner to secure the reinforcements and insulation to the pipe.

In the embodiment of the invention shown in Fig. 2, the sheet 7 is similar to the sheet 1, being curved transversely to fit the periphery of the insulation and the sheet is provided at its side edges and near its ends with slots 8, corresponding to the slots 2 of the Fig. 1 construction. A plurality 65 of series of lugs 9 are provided on the upper concave face of the sheet, the said lugs being struck up from the material of the sheet in the present instance. The lugs are of greatest width at their base and of less 70 width at their free ends, and they are formed by turning up the material between three slots perpendicular to the surface of the sheet. The lugs as shown are arranged in two series, the series corresponding in location to the location of the ribs 3. Both the ribs and the series of lugs are so spaced that they will engage the pipe far enough 75 to one side of a vertical line through the center of the pipe to prevent rolling of the 80 pipe. The ribs 3 may be cast on the sheet or they may be cast separately and afterward secured to the sheet.

As shown in Fig. 4, each rib 10 is on a strip 11, the strip being curved transversely 85 to fit the upper concave face of the sheet and the strips 11 are secured to the sheet by means of rivets or the like which pass through openings 12 at the ends of the strips. The ribs 10 do not extend to the 90 ends of the strip but are spaced apart far enough to provide room for the opening 12.

In Fig. 4, the strip 11 is of greater width than the base of the rib 10, so that there is a space between the side faces of the rib and 95 the side edges of the strip.

In Fig. 5 the rib 13 has an extended lug 14 at each end each lug having openings 15, for receiving rivets or the like to connect the ribs to the sheet. In this construction 100 the base of the rib is curved transversely to fit the upper concave face of the sheet, and the ribs as well as the strips 11 are secured to the sheet in spaced relation, so that they will engage the pipe in approximately the 105 same manner as shown in Fig. 3.

In the construction of Fig. 6, the ribs 16 are connected by a web 17 and the openings 18 for the rivets which connect the ribs to the sheet are in the web. The base of the 11

rib 16 and the web 17 is curved to fit the sheet and the ribs are spaced apart in the same manner as the ribs 3 of Fig. 1.

In Fig. 7 the ribs 19 are connected by a web 20, and each rib has a lateral extension 21 at its outer side. The extensions 21 are curved to fit against the concave face of the sheet but the base of the ribs and the web is plane or flat to provide a rest. The extensions 21 have the slots 22 near their ends for the tie bands.

In the construction of Fig. 8, the ribs 23 are connected by a web 24, and the base of the ribs and webs is flat or plane. In this arrangement as well as that of Fig. 7 since the ribs rest upon a flat surface or base the inner wall is of lesser height than the outer wall, so that the upper faces of the ribs will be inclined with respect to each other. The ribs and web are placed on the sheet 27 in the manner shown, and the sheet is bent up at each side of the outer face of the rib as indicated at 25 to prevent lateral movement. The side edges of the sheet are then bent outwardly and curved as indicated at 26 to fit the insulation of the pipe. The upper face of each of the ribs 1, 10, 13, 16, 19 and 23 is concave transversely to fit the periphery of the insulation, and the upper free ends of the lugs 9 are also concave for the same purpose. In use, the reinforcements are arranged with the ribs extending through the insulation into contact with the peripheral surface of the pipe. The ribs being of a height equal to the depth of the insulation, the concave face of the sheet will fit the outer face of the reinforcement closely. The tie bands are then placed and the reinforcement is in position to engage the pipe support. All of the weight of the pipe is borne by the ribs or the lugs and no part of the weight of the pipe comes on the insulation. It is obvious that the sheet might extend entirely around the pipe but this is not essential.

It will be evident that each construction comprises essentially the sheet shaped to fit and adapted to engage the periphery of the covering, and having means on its upper concave face adapted to extend through the covering into contact with the pipe for supporting the pipe, the said means being spaced apart from each other. In Fig. 4 the strip 11 is nothing more than the lugs 15 of Fig. 5, and may serve precisely the same purpose.

I claim:—

1. A device of the character specified, com-

prising a sheet curved transversely and provided with slots at its side edges, and ribs 61 on the concave face of the sheet and extending longitudinally thereof and spaced apart and parallel with respect to each other, the upper faces of the ribs being concave to fit the pipe and the sheet being curved to fit 65 the insulation of the pipe, said ribs being connected by an integral web, said web having openings for receiving securing means to connect the ribs to the sheet.

2. A device of the character specified, comprising a sheet curved transversely and provided with slots at its side edges, and ribs 70 on the concave face of the sheet and extending longitudinally thereof and spaced apart and parallel with respect to each other, the 75 upper faces of the ribs being concave to fit the pipe and the sheet being curved to fit the insulation of the pipe, each rib having an extension at each end, and each extension having an opening for receiving a securing means to permit the ribs to be connected to the sheet.

3. A device of the character specified, comprising a sheet curved transversely and provided with slots at its side edges, and ribs 85 on the concave face of the sheet and extending longitudinally thereof and spaced apart and parallel with respect to each other, the upper faces of the ribs being concave to fit the pipe and the sheet being curved to fit 90 the insulation of the pipe, said ribs being secured to the sheet.

4. A device of the character specified, comprising a sheet curved transversely and provided with slots at its side edges and ribs on 95 the concave face of the sheet and extending longitudinally thereof and spaced apart and parallel with respect to each other, the upper faces of the ribs being concave to fit the pipe and the sheet being curved to fit 100 the insulation of the pipe.

5. A device of the character specified, adapted to be connected to a pipe having an insulating cover, for supporting the pipe to prevent crushing of the insulation and comprising a sheet curved to fit the periphery of the covering and having ribs or extensions extending inwardly through the covering into contact with the pipe for supporting the said pipe to prevent the crushing of the covering.
